UNITED STATES PATENT OFFICE

167,243

AQUARIUM OR THE LIKE

Bernard Yellin, Chicago, Ill., assignor to Bernard Edward Co., Chicago, Ill., a corporation of Illinois

Application April 16, 1952, Serial No. 19,342

Term of patent 14 years

(Cl. D91—2)

To all whom it may concern:

Be it known that I, Bernard Yellin, a citizen of the United States, residing at Chicago, State of Illinois, have invented a new, original, and ornamental Design for an Aquarium or the like, of which the following is a specification, reference being had to the accompanying drawing, forming a part hereof.

Fig. 1 is a perspective view of an aquarium or the like, showing my new design.

Fig. 2 is a view partly in cross section taken on lines 2—2 of Fig. 1.

I claim:

The ornamental design for an aquarium or the like, as shown.

BERNARD YELLIN.
